UNITED STATES PATENT OFFICE.

HUMPHREY B. YOUNG, OF BROCKVILLE, ONTARIO, CANADA.

ATTACHMENT FOR BLACKSMITHS' ANVILS.

SPECIFICATION forming part of Letters Patent No. 397,530, dated February 12, 1889.

Application filed November 19, 1888, Serial No. 291,291. (No model.)

To all whom it may concern:

Be it known that I, HUMPHREY B. YOUNG, of Brockville, in the Province of Ontario, in the Dominion of Canada, have invented certain new and useful Improvements in Attachments to Blacksmiths' Anvils; and I do hereby declare that the following is a full, clear, and exact description of the same, reference being had to the accompanying drawings, in which—

Figure 1 is a side elevation of an anvil provided with my attachments. Fig. 2 is a top view of the same, and Fig. 3 is a perspective view of one of the attachments.

15 My invention has for its object to provide a blacksmith's anvil with attachments designed to hold horseshoes while finishing the calks, and for leveling the shoe.

20 My invention consists of an attachment comprising a horizontal arm parallel to one side of the anvil and secured at right angles to a leg passing horizontally through a transverse perforation in the anvil, a wedge adjustable in a slot near the projecting end of 25 said leg, to draw the leg endwise when the wedge is tightened and cause the arm to clamp the horseshoe against the side of the anvil, and a spring to react the arm when the wedge is loosened to release the shoe; also, 30 in the attachment to the square portion of the beak or horn of a blacksmith's anvil, for leveling or flattening a finished horseshoe, of a saddle having a flat surface flush with the face of the anvil and provided with a central 35 slot to receive the toe-calk, and a screw to clamp the saddle to the anvil.

A is the body of the anvil; B, the beak or horn; C, the square portion of the beak, and C' the heel portion of the anvil as now in ordinary use.

40 E E' are beveled depressions in the face of the anvil near the heel, and said depressions incline downwardly to the side, and are adapted to facilitate tapering the calks at 45 the heel or toe of a horseshoe when the shoe is in a vertical position at the side of the anvil by the calk bearing on one of the depressions while being hammered.

D is an arm parallel to one side of the anvil, and said arm is secured to the end of a leg, F, at right angles. The leg F passes through a horizontal aperture, G, in the side

of the anvil and projects from the opposite side, and said projection has a longitudinal slot, in which fits a flat wedge-shaped key, H, 55 which has frictional contact with the side of the anvil to draw arm D toward the anvil by driving or drawing down the key in the slot to clamp the horseshoe placed between the arm and anvil. If desired, the wedge-key H may be connected to a rod, I, attached to a foot-tread, J, to depress the wedge by pressure of the foot.

The arm D has an end extending past the leg F, and is provided with a finger, K, at 65 right angles to enter a hole, L, in the side of the anvil parallel to leg F, and said finger maintains the arm D horizontally.

M is a V or other shaped spring intervening the anvil and arm to throw out the arm 70 when the key is loosened.

N is a saddle attachment on top of the square portion of the beak, and said saddle has a flat top flush with the face of the anvil, and is secured removably by a clamp-screw, o, 75 impinging the side of the beak. The saddle is provided with a central slot or indentation, P, to receive a toe-calk while the shoe is being flattened or leveled on the face of the anvil by hammering.

80 I claim as my invention—

1. An anvil attachment comprising an arm, D, leg F, finger K, wedge H, and spring M, in combination with an anvil having a horizontal transverse perforation, G, through the 85 body and a hole, L, in the side, as set forth.

2. The combination, with a blacksmith's anvil having beveled depressions E E' and perforation G through the side, of the arm D, having a leg, F, provided with a longitudinal 90 slot near the end, a wedge-key, H, in said slot and in frictional contact with the side of the anvil, and a spring, M, as set forth.

3. The saddle N, having a flat surface at top flush with the face of the anvil, and provided with a slot, P, and clamping-screw o, in combination with an anvil having a beak or horn, B, provided with a square portion, C, as set forth.

HUMPHREY B. YOUNG.
